United States Patent Office

Des. 182,504
Patented Apr. 15, 1958

182,504

TYPEWRITER

Laird F. Covey, Monroe, Conn., assignor to Royal McBee Corporation, Port Chester, N. Y., a corporation of New York

Application September 19, 1957, Serial No. 47,780

Term of patent 7 years

(Cl. D64—11)

Fig.1

Fig.2

Des. 182,504

PAGE 2

Fig. 1 is a perspective view showing the front and right side of the typewriter.

Fig. 2 is a right side elevational view of the typewriter shown in Fig. 1 on an enlarged scale.

Fig. 3 is a rear perspective view of Fig. 1 on an enlarged scale, and

Fig. 4 is a top plan view.

The essential features of my design for a typewriter reside in the parts shown in full lines.

What is claimed is:

The ornamental design for a typewriter, substantially as shown and described.
